UNITED STATES PATENT OFFICE.

ISIDORE POLLINGHER, OF BOSTON, MASSACHUSETTS.

HORSESHOE.

1,083,889.

Specification of Letters Patent.

Patented Jan. 6, 1914.

Application filed July 23, 1912. Serial No. 711,100.

To all whom it may concern:

Be it known that I, ISIDORE POLLINGHER, a citizen of the United States, residing at Boston, in the county of Suffolk and State 5 of Massachusetts, have invented new and useful Improvements in Horseshoes, of which the following is a specification.

This invention relates to the class of horse shoes and more particularly to the class 10 wherein bands or straps are used instead of the usual nails.

An object of my invention is to provide a shoe of such novel and peculiar construction as to be easily and quickly fastened to 15 the hoof of a horse and securely held thereon by means of a strap.

Another object of my invention is to provide a shoe of such simple operation as to enable any man to attach the same to his horse 20 without the assistance of a blacksmith or other person skilled in the art of shoeing.

A further object of my invention is to provide a strap adapted to be fastened in such a manner as to firmly grasp the hoof 25 on all sides and to protect the back or tender part of the horse's hoof.

A still further object of my invention is to provide a shoe with a strap connection so constructed as to afford means whereby 30 the strap may be fastened without the use of a buckle.

With the foregoing and other objects in view my invention consists in such details of construction and arrangement of parts 35 as will be hereinafter more fully described and pointed out in the appended claims.

In describing my invention in detail reference will be had to the accompanying drawings wherein like characters denote 40 like or corresponding parts throughout the several views and in which:—

Figure 1 is a perspective view showing the application of the invention. Fig. 2 is a side elevation. Fig. 3 is a plan view. Fig. 45 4 is a detail view of the strap hook, and Fig. 5 is a section of the strap hook showing the strap connection.

In the drawings the numeral 1 designates the metal shoe shaped in the usual manner, 50 and having toe flanges or plates 2 and side flanges 3 projecting upwardly to hold the hoof 4 in correct position upon the shoe 1. Between the flanges 2 and 3 on each side of the shoe I provide upright members 5 and 6 55 so shaped as to lean one toward the other

and toward the front of the shoe, and each having a horizontal slot 7 at the top thereof. Near the rear of the shoe on each side thereof are similar uprights 8 and 9 also shaped to lean one toward the other but slightly 60 toward the rear or back of the shoe. These uprights 8 and 9 have perpendicular parallel slots 10, (preferably two) near the top thereof, the function of which, with the slots 7, will be hereinafter fully described. 65

The means provided for holding or securing the shoe 1 in place on the hoof comprises a strap 11 having one end secured as at 12 to the rear upright 8, from which point the strap 11 is broadened so as to form a pad 70

or cushion 13 for that part of the strap 11 which passes over the rear or tender parts of the hoof. After extending from the said upright 8 across the back of the hoof, the strap 11 is then passed around the second upright 75

9, through one of the perpendicular slots 10, and back again through the other slot 10 on the same upright, it then extends diagonally across the hoof to the front upright 5, over the top thereof, through the 80

slot 7, across the front of the hoof, into the slot 7 of the upright 6, from which point it again diagonally crosses the hoof so as to return to its starting point at the rear upright 8, where it is securely fastened by 85

means of a tongue 14 on the said upright 8. The strap 11 may be loosened or tightened by simply pulling the free end thereof and adjusting the strap over the said tongue 14 by means of holes 15 formed therein. 90

It will be seen from the above disclosure that the shoe may be easily and quickly removed or adjusted without the use of any tools whatsoever; that when once tightly hooked the shoe is securely held in place; 95 and that by reason of the special strap manipulation the hoof is universally gripped on all sides, thus producing a rigid and efficient means for holding the shoe in place.

The uprights, it will be observed are bent 100 so as to conform to the shape of a hoof and in which manner tend to hold the shoe in place, should the strap for any reason become loosened.

I desire it to be understood that I may make 105 slight changes in the combination and arrangement of parts without departing from the spirit of the invention provided such changes fall within the scope of the appended claims.

Having thus fully described my invention, what I claim as new, and desire to secure by Letters Patent, is:—

1. In a device of the character described, the combination, of a nailless horse shoe, uprights projecting from the front thereof and provided with horizontal slots, uprights projecting from the rear of said shoe and provided with spaced apart perpendicular slots, a strap, attached to one of said rear uprights and extending through all of said slots and means including a fastening element secured upon one of the rear supports between said spaced apart slots for engaging said strap substantially as described.
2. In a device of the character described, the combination, of a nailless horse shoe,

front uprights having a single horizontal slot at the top thereof and extending toward the front and toward each other, rear uprights having perpendicular slots at the top thereof and extending toward the rear and toward each other, a strap secured to one of said rear uprights and extending through all of said slots, a tongue carried by one of the rear uprights and adapted to hold the free end of the strap for fastening the shoe on the hoof, substantially as shown and for the purpose described.

ISIDORE POLLINGHER.
